UNITED STATES PATENT OFFICE.

JOHN WILLIAM NASMITH, OF HEATON MERSEY, MANCHESTER, ENGLAND.

COMBING MACHINE.

Application filed February 29, 1928. Serial No. 258,084.

In the United States specification No. 1,454,484 I have described and claimed a means for weighting the top leather covered detaching roller in a combing machine of the Nasmyth type, the weighting being effected in such a manner that the pressure on the said roller is reduced during that part of each stroke of the machine when such weighting is unnecessary, that is to say, when no detaching is taking place. The life of the leather covering of the top roller is thus prolonged.

The top roller in its detaching stroke and reverse stroke rolls bodily upon its lower metal roller, and in the specification No. 1,454,484 this combined with suitable accessories served to vary the tension of a spring 2 shown in Figures 1 and 2 of the drawings accompanying that specification. It is found in practice however that whilst the spring referred to adequately fulfills its function as a spring, there is a difficulty in obtaining commercially springs which are when new of the same tension or strength, and further, there is the danger that the screw adjustment of the spring tension may be tampered with by unauthorized persons, thus detracting from the industrial value of the device.

The object of the present improvements is to provide means for relieving the weight from the top roller with substantially the same accessories as those described in the specification No. 1,454,484 except that the spring is dispensed with, and in its stead there is provided a positive weighting means consisting of a weight or weights, the variation in pressure upon the top detaching roller depending upon the angle made by the said lever and its weight or weights as the top roller rolls to and fro.

In a convenient form the weighting is applied by means of two articulated arms forming the weight lever, the articulated ends being weighted to the desired extent and the accessories are so arranged that as through the movement of the parts, the lever arms assume the straight or horizontal position the pressure applied increases, the reverse taking place as, owing to the movement of the accessories of the machine and of the top roller, the articulated arms of the lever form an increasing angle to each other.

The improvements in this form will now be fully described reference being had to the accompanying drawing which shows the apparatus in side elevation.

Referring to the drawing which shows a combing head, C is the cylinder, R the rock shaft and P a fixed pin which are journalled in the frame head (not shown). This frame 60 also carries a bearing for the shaft S and the steel detaching rollers D, D'. On the shaft S is keyed the two armed lever L which is rocked to and fro from the rocking shaft R through the adjustable link N, the shaft R 65 being oscillated in the usual manner from a cam or eccentric in the machine headstock. The upper arm of the lever L carries a pin 1 upon which is loosely pivoted the weight hook H the other end of which bears upon the 70 neck of the leather covered top detaching roller d. Attached as shown to the lower part of the hook H is a tail member T.

Upon the pin P is pivoted the pendent arm 5 which supports one end of a long lever K 75 and the upper end of this lever K is by means of a hooked extremity pivoted loosely on the pin 1. All of these parts just described are substantially as shown in the prior specification and they form per se no part of these 80 present improvements, being inserted here for a clear understanding of the drawing. The adjustable spring which in that specification joins the lower end of lever K and the lower end of the tail T is dispensed with and 85 according to these present improvements a lever connects these two members, one of the arms of which w has a forked end provided with a pin 10 which hinges in a notch in the lower end of tail T. This arm w has also 90 fitted thereto a pin 11 which fits in a notched end of the arm W. The articulated ends of w, W are weighted at 12 as shown in the drawing.

The end of the arm W which is connected to the lever K is bifurcated and hinges on a pin 13 which engages in a slot 14 cast in the lever K and this pin is tapped to receive the screw 15 whereby its position in the slot 14 may be regulated.

The pendent swinging arm 5 is notched as shown at 16 and a knife edged support 17 carried by the lever K rests in the notch.

In the drawing, the parts are shown in the position assumed by them when the top detaching roller d is in its most forward position, when the greatest pressure upon it is required for detaching. At each stroke of the apparatus this roller moves between its full line and dotted line positions.

During the operation of the machine the lever L rocking to the left serves to bring for-

ward the pin 1 and thus the lever K, with the result that the lower end of this lever moves to the right and thus allows the arm w of the weight lever to drop at its inner and weighted end. The top roller d simultaneously moves to its dotted line position with consequent movement of the weight hook H and tail T, the arm W thus likewise dropping at its weighted end, and the whole lever w, 10 W assuming the dotted line position as seen in the drawing. At this point in the movement the pressure upon the top roller d is least and on the reverse or forward stroke the weight hook and K moving in the reverse 15 direction the articulated lever w. W is again pulled up to the full line position thus increasing the weight applied to the hook H and thus to the top roller.

By suitably dimensioning the various parts 20 and allowing the levers w and W to oscillate between their two extreme positions as the apparatus operates, a very small weighting will give the requisite pressure on the roller d, varying to the desired extent.

25 In the construction shown in the drawing the lever K serves to raise the weight hook from the top roller d when the latter is to be removed for any reason. For this purpose the lower end of the lever K is lifted to bring 30 the knife edge support 17 from its notch 16 and it is then allowed to drop, a face 7 formed thereon coming against a face 8 on the weight hook 11 and thus by the weight of the lever K forcing the curved end of the weight hook 35 from the neck of the top detaching roller d. This function of the lever K is however substantially described in the prior specification No. 1,454,484 and is not herein claimed.

The particular arrangement of weighting 40 shown allows of a light weight being applied with good weighting effect upon the top detaching roller, and the weighting and variation thereof will depend upon the angle which w makes to W when the articulated ends of 45 these members are at their highest point. The pull of the weighted ends of these members is very great if they are so dimensioned and arranged that they form a straight line when they reach such highest point and as will be 50 seen, if they were so arranged that the arm W dropped, on the non-detaching stroke of the top roller d, to a position in which it was nearly or quite in prolongation of the tail member T, the weighting of the hook H 55 would be small or entirely absent. The relative positions shown in the drawings are found efficient in practice.

I claim:—

1. In a combing machine of the Nasmith

type having a top detaching roller which rolls to and fro upon a lower roller, a weight hook one end of which is hung upon the top roller, weighting means for the said weight hook and means for lowering the said weighting means on the non-detaching stroke of the top roller to lessen the pull of such weighting means upon the hook and for raising the said weighting means to increase the pull of such weighting means upon the hook on the detaching stroke of the top roller, such 70 weight raising and lowering means being actuated synchronously with the movement of the said roller.

2. In a combing machine of the Nasmith type, having a top detaching roller which 75 rolls to and fro upon a lower roller, a weight hook one end of which is hung upon the top roller, a pivot support, a centrally articulated lever pivoted at one end to the support and at the other end pivotally supported by the 80 weight hook, the hook moving towards the pivot support during and as a result of the non-detaching movement of the top roller and vice versa, and weighting means borne by the lever adjacent to its articulation. 85

3. In a combing machine of the Nasmith type, having a top detaching roller which rolls to and fro upon a lower roller, a weight hook one end of which is hung upon the top roller, a pivot support formed upon a lever, 90 a centrally articulated lever pivoted at one end to the pivot support and at the other end supported by the weight hook, the hook moving towards the pivot support and the latter moving towards the hook during the non-detaching movement of the top roller and vice versa, weighting means borne by the lever adjacent to its articulation, and means for moving the pivot support-bearing lever synchronously with the top roller and its weight hook. 100

4. In a combing machine of the Nasmith type, having a top detaching roller which rolls to and fro upon a lower roller, a weight hook one end of which is hung upon the top detaching roller, a pivot support formed 105 upon a lever, a centrally articulated lever pivoted at one end to the pivot support and pivotally supported at the other end by the weight hook means for moving the pivoted support bearing lever towards the weight hook on the non-detaching movement of the top roller and vice-versa, and weighting means borne by the articulated lever adjacent to its articulation.

In testimony whereof I have hereunto set 115 my hand.

JOHN WILLIAM NASMITH.
